UNITED STATES PATENT OFFICE.

EVERETT L. BLAKESLEE, OF SEATTLE, WASHINGTON, ASSIGNOR TO AMERICAN BOTTLE CAP COMPANY.

BOTTLE CAP.

Application filed December 9, 1920. Serial No. 429,363.

To all whom it may concern:

Be it known that I, EVERETT L. BLAKESLEE, a citizen of the United States, and resident of the city of Seattle, county of 5 King, State of Washington, have invented certain new and useful Improvements in Bottle Caps, of which the following is a specification.

This invention relates to bottle caps, more 10 particularly to improvements in bottle caps of that type disclosed and claimed in the United States Patent Number 1,158,622, issued to me November 2, 1915.

I have discovered in the use of the cap 15 covered by the above mentioned patent that when the corking member used in capping the bottles draws the cap down upon the bottle rim, the apron of the cap has a decided tendency to open, or flare, and thus 20 leave an open space between the same and bottle rim wherein dirt may collect.

It has also been discovered that the flat 25 disk portion disclosed in the above patent does not co-act with the annular corking member as efficiently as does a slightly curved disk with a downwardly turned edge connecting with the annular corking member.

The object of the present invention is 30 therefore to provide a cap which avoids the above mentioned defects by the provision of an apron which shall be in contact along a continuous line upon the bottle lip for the purpose of absolutely excluding all dirt; to 35 produce a cap having a corking member possessing the greatest lateral elasticity possible to produce by means of the form or shape thereof in a non-distensible material, such as paper or the like.

40 In accomplishing these and other objects of the invention, I have provided the improved details of construction, the preferred forms of which are illustrated in the accompanying drawings, wherein—

45 Figure 1 is an elevation of a bottle with one form of the cap in place thereon; the cap and bottle being shown partly in section for better illustration.

Figure 2 is a similar view illustrating 50 an alternative or modified construction.

Referring more in detail to the drawings—

1 designates a bottle of the type for which the present cap is intended and which has 55 a rounded rim 2 surrounding the mouth

thereof, and a recessed, or dovetailed, annular interior surface 3 formed above an annular shoulder 4.

The cap embodied by the present invention, in its preferred construction, is formed 60 of an upwardly and outwardly convex disk portion 5 turned downwardly about the edge as at 6, and then radially as at 7, the latter portion thus forming an annular corking member adapted to fit into the 65 dovetailed portion of the rim and effectively cork the same.

The material of the cap is bent upwardly and inwardly from the portion 7, as shown 70 at 8, with the groove 9 upon the peripheral surface thereof, and is then turned outwardly from the portion 8 to form the protecting flange or apron 10; the spring or curvature of said apron being sharper or more abrupt at the inner portion than the 75 curvature of the corresponding portion of the bottle rim, in order that there will be a space 11 formed intermediate the apron and rim.

The apron is formed to engage the rim 80 upon an annular line near the periphery of the latter, as indicated at 12.

The result of the above construction is 85 that the several portions of the cap, viz: the disk 5, corking member 7 and apron 10 are given the greatest possible relative flexibility obtainable from a non-distensible material; that any pressure within the bottle 90 arising from decomposition of the contents thereof may easily distort the convex disk 95 7, thereby withdrawing the corking member 7 partially from its seat, and thus, by reason of the looseness thereof, give warning of undesirable conditions within the bottle; that the corking member, when forced radially 100 against the dovetailed face 3 produces a component force parallel to the axis of the bottle, thus drawing the cap down upon the bottle lip and causing the apron 10 to have a continuous line contact around said bottle lip.

The apron 10 may be constructed to only 105 partially cover the bottle lip 2, stopping substantially at the contact line 12, as shown in Figure 1; or it may be carried past contact line 12 and constructed to embrace the lip 2, as shown in Figure 2.

In the latter construction the apron is rendered elastic or yielding by means of indentures 13 therein, each indenture passing 110

2
partially through the thickness of the material, as disclosed and claimed in the above mentioned patent previously issued to me.

My invention may be made of any size and constructed of any material deemed convenient and suitable for a device of this character, and while I have illustrated and described a form of construction found desirable in materializing my invention, I wish to include in this application for Letters Patent all mechanical equivalents and substitutes that may fairly be considered to come within the scope and purview of my invention as defined in the appended claim.

15 Having thus disclosed my invention so that others skilled in the art may be enabled to construct and to use the same, what I claim as new therein and desire to secure by Letters Patent, is:

20 The combination with a bottle having a

rounded rim about the mouth thereof with a dovetailed, annular interior formed above an annular shoulder, of a cap for said bottle comprising a central concave disk portion turned downwardly about its edge and then 25 extending radially forming an annular corking member adapted to seat against said shoulder within the dovetailed interior of the neck, and being bent upwardly and inwardly above said corking portion and then 30 turned outwardly to form an annular groove just above the corking portion and then extended to form an apron having peripheral sealing contact with the outer surface of said bottle rim but spaced therefrom within 35 the periphery.

Signed at North Portland, Oregon, this 22nd day of November, 1920.

EVERETT L. BLAKESLEE.
